CLAIM

We claim the ornamental design for a cook sensor with cradle, as shown and described.

DESCRIPTION

FIG. 1 is a front perspective view of a cook sensor with cradle showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof; and,
FIG. 8 is an exploded front perspective view of the cook sensor with cradle in which the cook sensor is shown separated from the cradle.

The broken lines in the figures depict portions of the cook sensor with cradle which form no part of the claimed design.
